The ornamental design for a backhoe, as shown and described.

DESCRIPTION

FIG. 1 is front view of a backhoe showing our new design; FIG. 2 is a rear view thereof; FIG. 3 is a left side view thereof; FIG. 4 is a right side view thereof; FIG. 5 is a top view thereof; FIG. 6 is an upper left front perspective view thereof; and, FIG. 7 is an upper left rear perspective view thereof. A bottom view is omitted because it is plain and unornamental and forms no part of the subject matter of the claimed design.
